The ornamental design for a double-band nasal dilator, as shown and described.

DESCRIPTION

FIG. 1 is a top plan view of a first embodiment of a double-band nasal dilator showing our new design, the bottom plan view not seen in use;

FIG. 2 is a three-quarter perspective view thereof;

FIG. 3 is a perspective view thereof, showing the double-band nasal dilator in an in-use state;

FIG. 4 is a top plan view of a second embodiment of the double-band nasal dilator showing our new design, the bottom plan view not seen in use;

FIG. 5 is a three-quarter perspective view thereof; and,

FIG. 6 is a perspective view thereof, showing the double-band nasal dilator in an in-use state.

The broken line showing of human facial features is directed to environment and for illustrative purposes only; the broken lines form no part of the claimed design.
